UNITED STATES PATENT OFFICE.

WILLIAM HILLMAN, OF COVENTRY, ENGLAND.

DESIGN FOR A SADDLE-POST FOR BICYCLES.

SPECIFICATION forming part of Design No. 22,714, dated August 15, 1893

Application filed July 14, 1893. Serial No. 480,532. Term of patent 14 years. Patented in England January 2, 1892, No. 8,292; in France May 16, 1892, No. 221,653, and in Germany March 10, 1893, No. 12,431.

To all whom it may concern:

Be it known that I, WILLIAM HILLMAN, a subject of the Queen of Great Britain, residing at Coventry, in the county of Warwick, England, have invented and produced a new and original Design for the Saddle-Post of a Velocipede, of which the following is a specification, reference being had to the accompanying drawing, forming part thereof, the same

5 being patented in Great Britain January 2, 1892, No. 8,292; in France May 16, 1892, No. 221,653, and in Germany March 10, 1893, No. 12,431.

10 The drawing represents a side view of the saddle post of a velocipede. Heretofore the saddle posts of velocipedes have been constructed of plain tubes, which have been de-

void of ornamental appearance except such as may have been painted thereon or otherwise applied thereto, which of course involves additional expense.

15 The peculiar feature of my design consists of the helical or coiled configuration of the saddle post of a velocipede such as *a* in the drawing, which renders it highly ornamental.

I claim—

20 The design for a velocipede saddle post having the spiral configuration shown.

WILLIAM HILLMAN.
